INVENTOR,
JAMES W. INGRAM.

BY *James Ingram*,
ATTORNEY.

UNITED STATES PATENT OFFICE

JAMES W. INGRAM, OF SAN FRANCISCO, CALIFORNIA

BARBER'S COMB

Application filed July 16, 1930. Serial No. 463,255.

The present invention relates to improvements in combs, and more particularly to those employed by barbers in the prosecution of their calling.

As is well understood, the common practice in comb manufacture is to give to the back edge of the comb an approximately straight line or a line slightly convex, conditions depriving a barber using such combs of a secure thumb-rest as held in hand, ordinarily, by a barber in hair-trimming.

Another faulty condition in ordinary comb construction, as viewed from the barber's standpoint, lies in the fact that the comb's tooth-points lie substantially in a common straight line, making it difficult, on account of the blunt ends thus provided the comb, for the barber to lift the locks of hair from depressions and to readily reach that immediately behind the ears. These difficulties are eliminated in the present construction, the combs here having extremities whose teeth-points lie in a line curving from comb-extremity to comb-extremity with its convexity facing outwardly, thus removing that extreme bluntness of comb-ends usually found, and so objectionable, in comb constructions intended for barbers' use.

The primary objects of the present invention are to remedy the difficulties previously referred to by substituting a double-reverse curve for the comb back the central section of which has its convexity extending forwardly and its concavity milled to provide a suitable thumb-rest for the barber's thumb in gripping normally a section of the comb body, and, additionally, that of forming the teeth-points to lie within a gently curving line extending from comb-extremity to comb-extremity with its convexity facing outwardly.

The invention resides in the peculiar contour given to the comb's back edge and to the inward curving of the central section thereof and the milling borne thereby, together with the curving of the tooth-edge line extending from comb-extremity to comb-extremity with the convexity of the line facing outwardly and the narrowed bluntness of the comb ends.

In the accompanying drawings, forming a part of this specification, and in which like

reference characters refer to like parts, throughout:

Figure 1 represents a barber in the act of hair-trimming together with the comb as normally held in the hands of a barber while engaged in the act thereof;

Figure 2 is a blank form from which the comb is formed, showing the nature of the comb's back-curve, together with the extreme sweep of curve from comb-extremity to comb-extremity and the narrowed comb ends resulting from this construction; and

Figure 3 is a perspective view, approximately full size, of a comb constructed in accordance with my invention, showing both the character of the curve of the comb's back edge and the milling borne by the central section thereof, and, additionally, the character of the curve within which the teeth-points are made to lie and the narrowed comb ends.

Referring more particularly to the drawings, the numeral 4 indicates, in a general way, a barber in the act of hair-trimming; 5 indicating a normally held comb, 6 a pair of shears, 7 a lock of hair in the act of being trimmed, 8, 9 and 10 a double-reverse curve constituting the back edge of a blank from which a comb is formed, of which 9 is the central section thereof and 8 and 10 the reverse curved extensions therefrom, 11 and 12 the extreme ends and 11, 12 and 13 the slightly curved frontal edge, the convexity of which faces forwardly. In a comb proper, as represented in Figure 3, the double-reverse back edge curve is indicated by 14, 15, the central section being indicated at 16 with a milled edge 17 and having reversed curved sections 14 and 15 terminating at the comb ends 18 and 20, the tooth-sections being indicated at 23, 24, the points of the teeth constituting these sections conforming to a curve indicated at 18, 19 and 20 joining, respectively, at 18 and 20 the extremities of the curves 14 and 15 to form the somewhat narrowed extreme ends of the comb, these bearing the widened and strengthened initial end teeth 21 and 22 of the comb.

The blank represented in Figure 2 may be stamped from any suitable material, preferably from some form of aluminum sheet

material of a desired thickness and the blank thus obtained die-stamped to form the comb, or the comb may be directly die-cast.

Having thus described my invention, I claim, and desire to secure by Letters Patent of the United States, the following:

1. A barber's comb having a hand hold and a thumb-rest, said thumb-rest comprising a double-reverse curved portion for its back edge with the convexity of the central portion of said curve facing inwardly toward the body of said comb.

2. A barber's comb having a double-reverse curve for its back edge with the convexity of the central portion of said curve facing inwardly toward the body thereof, and with its concave surface milled to provide a secure thumb-rest.

3. In a comb of the character described, a comb-back having centrally a concavity facing outwardly, said concavity being milled and adapted to form a thumb-rest for the convenience of a barber manipulating said comb.

25 4. A barber's comb having a body and teeth extending outwardly therefrom the points of its teeth lying within a curve extending from extremity-to-extremity thereof, with the convexity of said curve facing outwardly from the body thereof the teeth in the center of the comb being shorter than those between the center and the extremities.

35 5. A barber's comb having for the edge of its back section a double-reverse curve, the convexity of the central portion of said curve facing inwardly toward the body thereof and milled on its concave edge, said body being provided upon its opposite edge with a multiple of teeth, the points of which lie 40 within a single curve extending from comb-extremity to comb-extremity, with the concavity of said curve extending outwardly from the body thereof with its end portions uniting with the end portions of the two 45 outlying curves of the double-reverse curve of its back edge to form slightly blunted comb-extremities bearing, respectively, an initial tooth of increased width and bodily strength.

50 6. A barber's comb having a back provided centrally with a concavity, said concavity being milled and facing outwardly to provide a secure thumb-rest for the convenience of a barber manipulating said comb, the extremities of said curve having extension curves of opposite curvature thereto and extending, respectively, to the extremities of said comb.

60 7. A barber's comb having its back and tooth edges bounded by curved lines meeting at the extremities of said comb on the median line thereof to form slightly blunted ends therefor, the central section of said back being concave and milled, and the

tooth-points lying in a single curve the convexity of which faces outwardly.

8. The combination, in a device of the character described, of an elongated body portion the outer edge of which conforms in contour to that of a double-reverse curve, the central portion being concave and milled and the curved extensions therefrom reversed as to curvature, and teeth borne by the opposite edge of said body portion, the points of said teeth lying within a curve extending from comb-extremity to comb-extremity with its convexity facing outwardly, the curve bounding the said tooth edges meeting the extremities of said extension curves and forming therewith slightly blunted comb ends bearing, respectively, a shortened and broadened initial tooth.

In testimony whereof I hereunto affix my signature.

JAMES W. INGRAM.
